UNITED STATES PATENT OFFICE.

JONATHAN T. BROWN, OF MARBLEHEAD, MASSACHUSETTS, ASSIGNOR TO OLIVER A. MILLER, OF BROCKTON, MASSACHUSETTS.

HINGED LAST.

SPECIFICATION forming part of Letters Patent No. 699,785, dated May 13, 1902.

Application filed April 9, 1900. Serial No. 12,171. (No model.)

To all whom it may concern:

Be it known that I, JONATHAN T. BROWN, a citizen of the United States, residing at Marblehead, in the county of Essex and State of 5 Massachusetts, have invented certain new and useful Improvements in Hinged Lasts, of which the following is a specification.

This invention has relation to sectional lasts in which the two sections are hinged together to permit the heel portion to be thrown up at an angle to the fore part to permit the easy insertion of the last into or its withdrawal from the shoe.

The object of the present invention is to provide a hinged last which may be employed practically throughout the entire process of constructing a shoe and which shall be capable of withstanding the various strains to which it is subjected during the process of 20 leveling, heeling, and slugging.

To these ends the invention consists of a last possessing certain features of improvement, which are clearly illustrated upon the drawings, described in the following specifications, and particularly pointed out in the claims hereunto appended.

Referring to the said drawings, Figure 1 represents a last embodying my invention. Fig. 2 represents a longitudinal section through the 30 same, the toe end of the fore part being omitted for lack of space. Fig. 3 represents a similar section and shows the two parts of the last at an angle to each other with the lock withdrawn by a suitable tool. Fig. 4 represents a view looking at the top of the last. Fig. 5 represents a section on the line 35 5 of Fig. 2. Fig. 6 represents a similar view with the lock drawn to an inoperative position. Fig. 7 represents a view looking at the 40 end of the fore part with the two members of the hinge separated. Fig. 8 represents a perspective view of the hinge detached. Fig. 9 represents a perspective view of the hinged member to which the fore part is secured. 45 Figs. 10, 11, and 12 represent a different embodiment of the invention.

On said drawings the fore part is indicated at *a* and the heel part at *b*. Their meeting ends are provided with engaging faces *a'* *b'*, 50 and with diverging faces *a²* *b²*, the planes of which intersect each other at the axis of the

pintle which unites the members of the hinge together. The hinge members are secured, respectively, to the toe part and the heel part, which are cut away or recessed to receive 55 them. The fore or toe part is provided with two separate cylindrical apertures *a³* *a⁴*, which are substantially parallel to each other and which, as illustrated, are in lines substantially perpendicular to the plane of the face *a'*. The 60 fore part is likewise provided with the groove *a⁵*, communicating with the apertures *a³* *a⁴*. The hinge member which is connected to the fore part is indicated at *c* and consists of a substantially flat plate having projected 65 from one edge two cylindrical pins *c'* *c²*, which are of a size to enable them to fit snugly in the apertures *a³* *a⁴*. Said pins are secured rigidly in place by similar pins or other fastening devices *d* *d'* passed transversely through the 70 fore part of the last. The hinge member which is secured in the heel part *b* consists of a heel-plate *e'*, which covers the entire bottom surface of the heel part, a boss *e²*, depending from the heel-plate, a tubular bushing *e³*, projecting downward from the middle of the boss, and the two forwardly-projecting webs or 75 plates *e⁴*. These parts are all made of one metallic mass, and being integral are rigid and unyielding. The plate or hinge member 80 *c* fits between the webs *e⁴* *e⁴* of the other hinge member and is pivoted therein by the pintle *f*, which, as said, has its axis lying in the line of intersection of the planes of the faces *a³* *b²*. The forward edges of the webs *e⁴* *e⁴* project 85 into the groove *a⁵* of the fore part, while the hinge member *c* is provided with the rearwardly-projecting end *c³*, which extends well into the groove which separates the webs *e⁴* *e⁴*. The said end *c³* constitutes a portion of the 90 locking mechanism which holds the fore part and the heel part securely in the positions illustrated in Figs. 1 and 2 and forms, as it were, a finger adapted to be engaged between a stationary abutment or member and a movable locking member, as will subsequently be described. The member *c* is likewise provided with a second finger *c⁴*, which projects at substantially a right angle to the finger *c³*, and it extends into a groove in the heel-plate *e'*, 95 as illustrated in Figs. 2 and 8, and its rear edge bears firmly against the heel-plate when 100

the heel part is thrown downward in the position shown in Fig. 2.

The heel-plate is of course recessed or cut away to receive the rear hinge member, and it will be noted by an examination of Figs. 2 and 3 that the tubular bushing e^3 projects from the top of the heel part a short distance, this being for a purpose to be subsequently described.

10 In the boss e^2 is formed a slot e^5 , which is substantially parallel to the face of the heel seat or plate, and said slot communicates with the interior of the hollow bushing e^3 by a hole or aperture e^6 . In the slot is placed a movable locking member, which consists of a slide g , held normally forward in locking position by a compression-spring h , having one end inserted in a socket in said slide and having its other end connected to a screw-pin h' , projecting from the inner face of the heel-plate. The said slide or locking member is provided with the central aperture, one wall of which is inclined, as indicated at g' , and said aperture lies in line with the hole e^6 , so that by 25 inserting a tool consisting of a pin through the hollow bearing and the hole e^6 to bring the end of the pin against the inclined wall g' pressure against said pin will cause the withdrawal of the locking member into inoperative position. The movable locking member coacts with the finger c^3 , being so located that when the heel part is in the position shown in Fig. 1 or in Fig. 2 relatively to the fore part the locking member will be sprung forward to overlap the upper edge of the finger and prevent the heel part from being swung about the pintle f relatively to the fore part.

In order to stiffen the last and prevent too great strain upon the pintle f , an abutment 40 or stationary member j is employed and is located in the path of the finger c^3 . The abutment consists of a stud j , passed through the webs e^4 , and it is so placed as to be engaged when the faces $a' b'$ of the parts $a b$ meet, the said finger being of a diameter equal to the distance between the abutment j and the movable lock g .

The finger c^4 engages the heel plate simultaneously with the engagement of the abutment by the finger c^3 , so that the entire strain to which the last is subjected in leveling is borne principally by the hinge.

The overlapping webs of the hinge furnish a large area of engagement between the hinge members and securely hold the fore part and the heel part against sidewise or torsional movements with relation to each other.

The heel plate is provided with a pocket at the center of its surface to receive a plug 60 n , into which tacks may be driven in attaching an insole to the last. The plug is prefer-

ably formed of leather or equivalent material capable of frictionally holding the ends of the tacks which are driven therein.

In Figs. 11 and 12 a different embodiment 65 of the invention is illustrated, in which the sliding lock m is cylindrical and is held from rotation by a screw m' projecting into a slot therein. The spring m^2 is in a sleeve m^3 , secured to the hinge member by the said screw m' . In this form of the invention I dispense with the finger to engage the heel-plate, although I retain the abutment or stop for the lock-engaging finger.

Having thus explained the nature of the 75 invention and the way of constructing and using the same, without attempting to set forth all the forms in which it may be made or all of the modes of its use, I now declare that what I claim is—

1. A hinged last having a fore part, a heel part, and a hinge connecting said parts, said hinge comprising two members of which one is provided with a finger or projection and the other is formed with a stationary abutment and a movable lock adapted to receive said finger or projection between them.

2. A hinged last having a hinge comprising two members secured in the respective parts of the last, and a pintle connecting said hinge 90 members, the member for the heel part carrying a sliding lock movable longitudinally of the last, and the member for the fore part having a projection extending rearwardly and adapted to be engaged by the lock.

3. A hinged last having a hinge comprising two members and a pintle, the member for the heel part having two forwardly-projecting webs, and the member for the fore part having a web lying between the first-mentioned webs and pivoted therein by the pintle, the first-mentioned member having a lock movable longitudinally of the last into engagement with the web of the second-mentioned member.

4. A hinged last having a hinge comprising two members connected by a pintle, the member for the fore part having a rearwardly-projecting web, and the member for the heel part having parallel webs to receive the web 110 of the first-mentioned member, said member for the heel part also having a stop to limit the movement of the other member when it has reached the extreme of its movement, and a lock to hold said other member against 115 said stop.

In testimony whereof I have affixed my signature in presence of two witnesses.

JONATHAN T. BROWN.
